METAL WHEEL

Carolus L. Eksergian, Detroit, Mich., assignor to
The Budd Company, Philadelphia, Pa., a corporation of Pennsylvania

Application June 21, 1943, Serial No. 491,699

3 Claims. (Cl. 74—230.8)

1

This invention relates to a metal wheel, and has as an object the provision of a wheel of this type having radial rigidity and limited axial flexibility. The wheel of the invention is claimed in this application, whereas the preferred apparatus by which it is manufactured is claimed in the patent to Harold A. Strickland, Jr., 2,402,509, granted June 18, 1946. A feature of the invention consists in provision of a wheel having a hardened intermediate zone which may best be produced by the induction heating machine claimed in said patent and also described hereinafter.

In the heat treatment of metal products by inductive methods, it is frequently desirable to limit the extent of heat application to predetermined areas. In the case of wheels, for example, it may be desirable to heat treat the periphery thereof without disturbing the web or interior supporting structure.

Among the features of the present invention is the provision of a wheel having an annular edge area rendered relatively hard and rigid without internal modification of the interior supporting web. This may be made by use of inductive heating means that may be applied to a circular object in an annular area intermediate the edge and center. In this operation heat treatment is effected on an integral metal wheel structure without producing axial distortion of the metal. Effective quenching means is provided without disturbing the requisite proximity of treated area and heat producing coils.

An arrangement of apparatus and a specific form of preferred product are described in the following specification and shown in the accompanying drawings, in which

Fig. 1 is a side elevation in part section of the heating apparatus including also a section of a wheel inserted for treatment;

Fig. 2 is a plan view of the apparatus with the wheel and wheel lock removed;

Fig. 3 is a detail section showing in- and out-leads for electrical and cooling media;

Fig. 4 is a detail section showing a coil support; and

Fig. 5 is a detail showing a modified quenching apparatus.

Referring particularly to Figures 1 and 2, there is disclosed an inductive heating apparatus intended primarily for the heat treatment of circular bodies or articles such as wheels, rims and the like. On the base plate 10 is mounted by supports 11 the flange generally indicated by the numeral 12. The base plate 10 is in the general

2

shape of a flattened disc and is hollow in sections to form a reservoir 15 for the quenching fluid 13, the inlet pipe connection to the reservoir of the base plate being at 14. There is attached at the base periphery the upwardly extending front and side flange 16 forming with the back plate 17 a pan shaped receptacle for quench fluid after egress from the quenching nozzles. The back plate 17 is adapted to extend above the heating apparatus and forms a support for the transformer (not shown), lead in bus bars and other auxiliary equipment forming a part of the complete heating apparatus assembly. The flange 16 is attached to the base section of the base plate 15 by means of bolts 18.

The central section of the base plate 12 is apertured and extended on the upper side in a tubular support member 19 internally threaded at its upper end. Positioned within the tubular member 19 is a work support generally indicated by the numeral 20. This support includes a stub shaft 21 positioned within the tubular member 19 and supported therein by means of ball bearing units at the upper and lower ends of the tubular support 19. To provide for the ball bearing connection as mentioned, the support 19 at its upper end is formed with annular recesses 22 and 23, the recess 22 being adapted to receive a ring shaped bearing 24 having ball bearing runways formed therein and adapted in conjunction with a smaller ring 25 fixed on shaft 21, having outwardly formed runways therein to hold ball bearings 26 in operative relationship. The ring 25 is mounted on a section of the stub shaft 21 of reduced diameter, the edge formed by this section supporting the ring 25 in position. Immediately above the ring 22, in screw threaded engagement with the end surface of the tube 19 is a nut 27 which is adapted to hold the ring 22 in fixed position upon the end of the tube 19.

The lower end of the stub shaft section 21 is supported with reference to the base plate 10 by means of the ball bearing unit 60 including the runways rings 61 and 62 and ball bearings 63. The ring 61 is fastened directly to the shaft 21 and the ring 62 is secured in position by the locking wire 64. The stub shaft 21 is apertured on its lower end to receive an operating shaft 65.

Fixed to the shaft 21 directly above the inner ring 25 is a circular work support plate 30 having an annular edge extension beyond the external boundary of the supporting tube 19. Skirt 31 is fastened to the under side of the plate 30, the same enclosing the support 19 and extending downwardly to a zone adjacent the base plate 10.

Directly above plate 30 is positioned the work centering head 30a, the same being in the shape of a short cylinder provided with bayonet slots 32 on the periphery thereof. This head is held in position on the shaft by means of the terminal nut 34 which is screw threaded to the end of the shaft 21 and holds the head and various other units securely on the shaft end. A washer 33 separates the nut 34 from the head 31.

Means are provided for clamping the work piece in position on the work centering head 30a in the work clamping member 40, the latter comprises a ring 41 provided with pins 42 adapted to move into, and be secured by the bayonet slots 32. The ring 41 is connected to the top clamp section 43 by means of bolts 44 spaced from the ring 41 by means of tubular spacers 45.

The work piece as illustrated in Figure 1 of the drawing and which is adapted for heat treatment by the described apparatus is a sheet metal wheel 50, commonly referred to in the trade as a bogie wheel, a primary purpose of which is to serve as a guide wheel for heavy traction and automotive apparatus such as tanks and which is consequently subjected to severe treatment in use. Ordinarily these wheels undergo heavy radial axial or lateral stresses so that not only must the bearing rim of the wheel be sufficiently hard to resist road impacts and nicking, but also the web or body of the wheel must possess sufficient elasticity or resiliency to permit lateral yielding when the wheel is subjected to severe lateral stresses. As illustrated this wheel consists of a single metal disc, the same having a flattened hub section, a peripheral road bearing section having hardened metal areas and an intermediate sigmoid section joining the hub and edge sections. Preferably the hub section 51 is formed with apertures annularly displaced adapted to receive the heads of studs 52, the latter being threaded into apertured extensions 54 formed about the edge of the support plate 30. These studs serve as direct supporting means for the wheel upon the plate 30. The sigmoid section 55 includes two reversely curved annular segments connected by a flattened area, the same being approximately S-shaped. The edge section 56 is approximately V-shaped with the V opening toward the hub of the wheel. One segment of the V, 57, joins the sigmoid and is inclined angularly relative to the radial hub section. The other segment 58 of the edge section also is inclined relative to the hub section, forming a reversely turned rim for the wheel. As described to this point, it is apparent that the wheel may be mounted upon the rotatable stub shaft 21 upon which it is radially secured by means of the support plate 30, the centering head 30a and the clamping member 40.

Heat means 66 for the work piece is provided in a single turn inductor 67 which is supported from the base plate 10 by standards 78 connected through insulation 85 to the inductor lugs 86 in the shape of a hollow tube adapted to receive and transmit the cooling fluid 68. One face 69 of the inductor tube is flattened and angularly positioned with reference to the base plate 10 so as to lie in acute angular relationship to the edge section of the heating coil. The ends of the single coil 67 are led outwardly as shown particularly in Figure 3 to form terminals 70 and 71. These terminals contain ducts 72 and 73 which have connection to the communicating inlet and outlet ducts 74 and 75 for supplying a coolant to the inductor coil. These terminals

are also directly connected to the brackets 76 from which bus bar connection is made to the transformer. These brackets are also provided with ducts 77 which communicate with the terminals as shown in Figure 1.

Quenching means for the heating apparatus is provided by a plurality of annularly displaced standpipes 80 which at their bases communicate with the reservoir 13 in the base plate 10 in the area intermediate the stub shaft 21 and the standards 78. The outlet ends of these stand pipes 80 terminate adjacent the inner edge of the inductor coil 67 and adjacent these ends the pipes are provided with outwardly positioned spray nozzles of such shape as to throw under pressure a fan-shaped stream of fluid against the rotating surface section 57 of the wheel. Obviously, when the wheel is rotating at a high speed, there is added to the normally radial outward pressure acting on the fluid, a centrifugal force due to the wheel rotation, so that the tendency to force the fluid by the adjacent wheel surface is pronounced.

In the operation of the heat treatment apparatus the workpiece such as the wheel illustrated is placed in position and rotative power applied. Alternating currents are then led into the inductor circuit, which may be of a frequency in the order of 3000 cycles. The inductive action of the current in the inductor coil 67 heats the adjacent surface 57 of the wheel to a temperature above the critical point for the metal at which temperature it is preferably held a short time period such as five seconds depending on the characteristics of the steel; after which with the wheel still rotating the quenching fluid is applied. As previously mentioned the normal pressure of the fluid combined with the centrifugal rotative action of the wheel causes rapid outflow of fluid which is normally of sufficient force to prevent the formation of steam pockets. This rapid flow of cooling fluid rapidly reduces the metal temperature, a time period of six seconds being usual for a wheel as described, and imparts to the metal section 57 a desired degree of hardness. It is noted that the control over the degree of hardness may be secured either by control of the force of the quenching nozzles or by the degree of maintenance of the current in the inductor coil during the initial quenching operation. It is pointed out that the speed of heat application to wheel surface 57 is such that only a limited depth of material is heated. Accordingly, a steep temperature gradient is formed between surface 57 and the back surface, and on cooling advantage is derived from the relatively cool backing as an auxiliary quenching medium to accomplish rapid cooling of the surface 57.

A wheel made according to the described process possesses adequate edge hardness for resistance to impact and at the same time yields in the web so as to absorb radial and axial shock stresses. As appears from the process, the intermediate annulus 57 is the wheel area of greatest hardness. The annuli 55 and 58 bounding the annulus 57 are of lesser hardness and greater flexibility since these areas are out of the direct path of the quench stream. It is pointed out that the wheel is readily and firmly placed into and out of position; that the rotatable mount insures a uniformity in both heat and quench; and that through the hydraulic head as well as the centrifugal force of rotation the spray quench is forced quickly past the juxtaposed surfaces insuring a reduced formation of static steam pockets.

Figure 5 illustrates a modified form of quenching apparatus nozzle and inductor heating surface. In this modification instead of a slit nozzle stand pipe 80 a tubular nozzle 90 projects outwardly at an angle in direct line with the plane of the section 57 of the wheel to be heated, the nozzle terminating approximately at the inner edge of the inductor coil 91. The pipe surface 92 of the coil 91 instead of being formed with a straight-section fluid surface includes a curved section 93 forming an offset between a lower straight section 94 and a higher straight section 95, the inclination of the straight surface 94 and 95 being approximately the same and the curvature of the section 93 of the inductor being approximately the same as the adjacent edge section of the wheel. With this arrangement it is possible to force the quench fluid between inductor and wheel surface with greater velocity and to extend the hardened area of the wheel to a point nearer an extreme outer edge of the same.

While the term "wheel" is used with reference to the specific showing of the drawing, it is understood that in the claims the meaning is broadened to include any disc-like article subject to similar methods of heat treatment.

The term "web" as used in the claims is intended to describe the wheel area between the rim annulus 57 and the hub aperture.

Modifications of the invention other than that shown may of course be made and no limitation therefore is intended in the described embodiments other than that which is required by the scope of claims hereto appended.

What is claimed is:

1. A wheel comprising a hub section, a sigmoid section outwardly joining said hub section,

and an edge section outwardly joining said sigmoid section, said edge section including a rigid strip annulus adjoining said sigmoid section and a re-entrant annulus adjoining said rigid annulus, 5 the re-entrant annulus and sigmoid section being flexible relative to said rigid annulus.

2. A wheel comprising a hub section, an edge section, and a sigmoid section between the hub and edge sections, said edge section including 10 two annulus segments edge-joined at the wheel periphery, one of said segments having a free edge displaced inwardly from the periphery toward the wheel axis, said edge segment being softer than the joined segment.

15 3. A wheel formed of a single sheet of metal, said sheet having three concentric annuli, the edge and intermediate annuli forming the peripheral wheel rim surface and the intermediate annulus having greater hardness and less resiliency than the other annuli.
